FOLDED BAG

Oscar W. Lewis, Rumford, Maine, assignor to
Continental Paper and Bag Corporation, New
York, N. Y., a corporation of Delaware

Application December 17, 1931
Serial No. 531,588

4 Claims. (Cl. 229—88)

This invention relates to a receptacle and more particularly to an envelope or container adapted to be used as a cover for an article to be suspended from above, such as a bunch of bananas.

In the transportation and storage of bananas, it is often desirable to enclose the bunch of bananas within a covering of paper or other suitable material. Since the bunch of bananas is ordinarily suspended from above by a cord attached to the stalk, it is desirable to have an opening at the top of the envelope to receive the stalk or the cord.

It is an object of this invention to provide an improved envelope adapted to be used for this purpose. A further object is to produce an envelope which may be expanded to fit over different sized articles and which is reinforced in its upper portion. It is also an object to provide an improved method for folding the upper portion 20 of an envelope of this type. Other objects will become apparent.

In describing the invention reference will be made to the drawing in which Figure 1 represents a fractional perspective view of the upper portion 25 of an envelope during the first step of the folding operation. Figure 2 is a fractional side elevation of the top portion of the tube shown in Figure 1, at a later stage in the folding of the top portion. Figure 3 is a similar view of the upper portion of 30 the completed envelope. Figure 4 is a diagrammatic sketch indicating the manner in which the bag is folded. Figure 5 is a diagrammatic end view of the completed bag shown in Figure 3.

In producing an envelope embodying my invention, the top of the paper tube 10, which is open at each end, is folded in at each side, as indicated at 11, 11 in Figure 1. The top margin at one side of the tube is then folded back against the tube along the line 12, as indicated by the arrows *a*, *a* in Figure 4, to the position indicated in Figure 2. In folding back the doubled portions at the ends of this top margin, as just described, the corners 13, 13 are folded outwardly along the lines 14, 14. The top margin on the other side of the tube is then folded back against the tube along the line 15, as indicated by the arrows *b*, *b* in Figure 4. During this operation the corners 13, 13 are folded over along the lines 16, 16 to the position shown in Figures 3 and 5.

If further reinforcement of the upper portion of the bag is deemed advisable, a strip 17 of cardboard or other suitable material may be inserted under each of the folded back top portions of the tube, as shown in Figure 3 and Figure 5. The staples 18 may then be fixed in the upper folded

portions of the bag to further reinforce such portions and to maintain them in the folded position.

The envelope produced in this manner will have a reinforced upper edge surrounding an opening 19 in the upper end, which opening may be expanded to receive the stalk of the bunch of bananas or the means for suspending any other article with which the envelope is used.

The tube with the reinforced top margin, as above described, may be of any desired length 65 and may have its bottom portion open or closed. The upper edges of the paper tube may be folded back for a greater or a less length, to obtain the desired width of reinforcing. By increasing the length of the fold the overlapping triangles, 70 formed by folding the points 13, 13 outwardly, may be extended until they cover the entire upper edge of the tube at each side of the opening 19. When this amount of the tube is folded back, it may be desired to refold this folded edge 75 along lines parallel to and between the lines 12 or 15 and the corresponding upper edges of the bag. By this means additional reinforcement may be had at the upper edge of the tube, or this type or reinforcement may be substituted for the inserted cardboard strips 17, 17.

By folding the tube as described, the inwardly folded portions 11 will permit the expansion of the envelope in order that it may be readily slipped over the bulging portion of an article and 85 so that it will fit snugly around the article. The folded edge at the top of the tube gives a reinforced upper margin which will better withstand the strains to which it is subjected during use.

In illustrating the invention the corners 13, 90 13 have been shown as folded outwardly along the line 12 so that the halves of the top edge may be folded over symmetrically. If preferred, these corners may be folded so that the line connecting the ends of the folds 14, 14 extends at 95 an angle to the sides of the tube rather than parallel to it as shown. Also, if it is desired to have the opening 19 offset from the center of the top of the tube, this may be accomplished by folding the portions 11, 11 inwardly for different distances to the extremities of the desired opening, after which the top edge may be folded back as described. The portions 11, 11 may also be folded inwardly so that the front portions of the tube will be shorter than the rear portion, or vice versa, after which the top edge may be folded back as described.

It is apparent that many modifications of my invention may be made to produce a tube of 110 the desired configuration and it is not intended

to limit the invention to the particular embodiment described. The terms used in the description and claims are used in their descriptive sense and not as terms of limitation, it being intended to include all their equivalents within the scope of the appended claims.

I claim:

1. A tubular container having its sides folded inwardly lengthwise of the container and the opposed front and rear portions folded back against themselves, the inwardly folded portions forming spaced triangular reenforcements, at the outsides of the folded portions and extending over the end of the container.
- 15 2. A tubular container having its sides folded inwardly lengthwise of the container and the opposed front and rear portions folded back against themselves, the inwardly folded portions forming spaced triangular reenforcements, at the 20 outsides of the folded portions.

3. A tubular container having its sides folded inwardly lengthwise of the container and the opposed front and rear portions folded back against themselves, the inwardly folded portions forming spaced triangular reenforcements, at the outsides of the folded portions, and independent securing means extending through said triangular portions.

4. A tubular container having its sides folded inwardly lengthwise of the container and the opposed front and rear portions folded back against themselves, the inwardly folded portions forming spaced triangular reenforcements, at the outsides of the folded portions, and an independent strip of reenforcing material between the folded back portions and the body of the container, and securing means extending through said triangular portions and strip.
